RATCHET DEVICE

Theodore O. Rueb, Chicago, Ill., assignor to The Sherman-Klove Co., Chicago, Ill., a corporation of Delaware

Application October 14, 1938, Serial No. 235,003

5 Claims. (Cl. 192—43.1)

This invention relates to wrenches of the type in which the handle is operatively connected with a rotatable head or driven member by means of ratchet and pawl mechanism constructed so that the movement of the driven member may be reversed or rotated in either direction by the vibrating movement of the handle.

The objects of this invention are primarily to produce an improved wrench of this character which will be particularly sturdy and substantial in construction and simple and efficient in operation.

Other objects are to provide an improved reversing mechanism for changing the position and ratcheting action of the pawl, and such other advantages as will appear more fully from the following description.

In the accompanying drawing illustrating this invention,

20 Figure 1 is a plan view of the wrench showing the handle broken away;

Figure 2 is a sectional view taken on the line 2—2 of Figure 1;

25 Figure 3 is a sectional view taken on the line 3—3 of Figure 2;

Figure 4 is a view similar to Figure 3 but showing the pawl in reverse position;

Figure 5 is a sectional view taken on the line 5—5 of Figure 2; and

30 Figure 6 is a view showing parts of the reversing device in disassembled position.

The wrench 7 has a barrel or cylindrical head 8 provided with a handle which may be formed integrally therewith or secured thereto in any desired manner. The barrel 8 is closed at one end by a head 9 preferably formed integrally therewith. It is also provided in the central portion with ratchet teeth 10 which are adapted to be operatively engaged by teeth 11 and 12 in the opposite ends of a reversible pawl 13. The pawl 13 is mounted in a recess 14 in the longitudinally central portion of a work-engaging head or driven member 15 which is rotatably mounted in the barrel or driving member 8 as shown particularly in Figure 2. The driven member may be held in rotatable position by any suitable means as by means of a spring ring 16 which coacts with these parts to hold them together. The driven member 15 may be connected with the nut or article to be turned in any suitable manner, having a projection 17 of the type commonly used for engagement with sockets or the like as indicated at 18.

The pawl 13 is pivotally mounted on a pin 19 secured in the driven member 15 so that either

end thereof may be moved into ratcheting engagement with the teeth of the driving member. The pawl is reversed and either end also held in ratcheting position by means of a pin or plunger 20 having its projecting end rounded to engage with a curved surface 21 on the adjacent portion of the pawl as shown in Figures 3 and 4. The plunger 20 is carried in a socket 22 which is closed at one end, and is urged outwardly by a compression spring 23 which holds it in operative position. The socket 22 engages with a transverse hole 24 in a short shaft 25 which is rotatably mounted in a bearing 26 in the center of the driven member, being co-axial therewith. The socket 22 has an outwardly extending flange 27 at one end for engagement with the flattened side of the shaft as shown. The shaft 25 has a transverse blade or key 28 that fits in a slot or keyway 29 in a disc 30. The shaft also has a round central trunnion 31 that fits in a bearing 32 in said disc. The disc 30 has a peripheral shoulder 33 so that the upper portion thereof is of smaller diameter than the lower portion.

The lower portion of the disc fits in an annular recess 34 in the driven member 15 and the smaller portion of the disc fits in the hole or bearing 35 in the cap or head portion 9. The arrangement of these inter-fitting parts is such that they are all held in alignment to insure proper operation. The disc 30 is provided on its upper surface with a transverse projection or fingerpiece 36 for turning the same.

It will be noted that the socket 22 projects a substantial distance through the shaft 25 as shown in Figs. 3 and 4 and stop members such as pins 37 and 38 are provided in the driven member 15 to limit the swinging movement of the shaft 25 when it is turned to reverse the pawl.

The operation of the wrench will be readily apparent to those familiar with these tools. When the driven member is to be turned in one direction the user rotates the shaft 25 by means of the finger-piece 36 to swing the plunger 20 past dead-center for instance as shown in Figure 3. When it is desired to rotate the driven member in the opposite direction the shaft 25 is rotated past dead-center or the position shown in Figure 4, the stop pins 37 and 38 serving to limit the movement in the respective directions. When the plunger is in either of these operating positions the spring 23 tends to urge it toward the pawl and consequently keep the corresponding end of the pawl in resilient or ratcheting engagement with the teeth of the driving member.

The various parts of the wrench may be made of any suitable material for the purposes intended and changes may be made in the details of construction or particular arrangement of the parts 5 to adapt the wrench for different uses without departing from the scope of the invention.

What I claim is:

1. A ratchet device comprising a driving member, a driven member rotatably mounted in the 10 driving member, a double ended pawl pivotally mounted in the driven member adjacent to one side thereof and having teeth in the opposite ends, an annular series of teeth in the driving member for engagement with the respective ends 15 of the pawl, a shaft rotatably mounted in the driven member and co-axial therewith, a transverse socket mounted in the shaft, a plunger in said socket, a spring coacting with the socket and plunger and serving to press the plunger 20 against an adjacent curved surface in the pawl for swinging the pawl, means for manually rotating the shaft, and means for limiting the rotational movement thereof whereby the plunger will coact with one or the other end of the pawl 25 when swung to operative position.
2. In a ratchet device, the combination of a driving member including a barrel having teeth projecting inwardly therein, a driven member rotatably mounted in the barrel, means for holding 30 said driven member in the barrel, a pawl mounted in a transverse recess in the driven member, a pin in the driven member adjacent to one side thereof on which the pawl is mounted, said pawl having a curved surface opposite to 35 the axis of the driven member, a shaft mounted in the driven member co-axially therewith, a transverse support in the shaft, a spring plunger in said support which engages with the said curved surface to swing the pawl and hold it in ratcheting positions, a transverse key at one end 40 of said shaft, a center trunnion projecting from the key, a disc rotatably mounted in the driven member and having a transverse slot for receiving said key and a center bearing for receiving 45 said trunnion, said disc also having a portion engaging with a bearing in the end of the barrel, and a finger-piece projecting from said disc for actuating the same.

3. A device as per claim 2 in which the plunger shaft is flattened at one side, the socket projecting through a transverse hole in said shaft and having a flange engaging with said flattened surface. 5

4. A ratchet device comprising a barrel adapted to be actuated by a handle or the like and having a head at one end with a center hole therein and having a peripheral series of ratchet teeth projecting inwardly, a disc rotatably mounted in the hole in the head, a finger-piece 10 projecting from said disc for rotating the same, a driven member for turning a part to be acted upon, rotatably mounted in the barrel and having a recess forming a bearing for said disc, a short shaft rotatably mounted in the driven member, a projection on said shaft engaging with a transverse slot in the disc, a spring plunger mounted laterally in the shaft, means in the driven member for limiting the rotating movement of said shaft, a double-ended pawl pivotally 15 mounted in a transverse opening in the driven member and adapted to have its ends engage with the teeth in said barrel, said pawl having a curved surface which is engaged by the spring plunger for swinging the pawl to operating positions and holding it in ratcheting engagement with the teeth and a spring ring engaging with the barrel and driven member for holding the driven member and parts associated therewith in operating position in the barrel. 20 25

5. In a ratchet device, the combination of a barrel having inwardly projecting teeth therein, a driven member rotatably mounted in the barrel, a pawl pivotally mounted in the driven member and having oppositely disposed engaging portions for engagement with the teeth whereby the driven member may be turned in opposite directions, an operating disc positioned within the barrel and having a bearing in the driven member and also having a bearing in the end of the 40 barrel, and means coacting with the disc and the pawl for moving the pawl to its respective operating positions and holding the same with the corresponding end in resilient engagement with said teeth. 35 45
